UNITED STATES PATENT OFFICE.

BESSIE M. SMITH WALSH, OF SHERIDAN, WYOMING.

DESIGN FOR AN ARM-REST.

49,134.

Specification for Design.

Patented May 30, 1916.

Application filed December 31, 1915. Serial No. 69,681. Term of patent 7 years.

To all whom it may concern:

Be it known that I, BESSIE M. SMITH WALSH, a citizen of the United States, residing at Sheridan, in the county of Sheridan and State of Wyoming, have invented a new, original, and ornamental Design for Arm-Rests, of which the following is a specification, reference being had to the accompanying drawing, forming part thereof.

Figure 1 is a perspective view of an arm rest showing my new design; Fig. 2 is an

end elevation thereof; Fig. 3 is a side elevation thereof; Fig. 4 is a top plan view thereof.

I claim:

The ornamental design for an arm rest, as shown.

BESSIE M. SMITH WALSH.

Witnesses:

W. E. DALE,
H. E. ZULLIG.
